UNITED STATES PATENT OFFICE.

JOHN Q. C. SEARLE, OF CHICAGO, ILLINOIS.

CAR-WARMER.

SPECIFICATION forming part of Letters Patent No. 311,533, dated February 3, 1885.

Application filed February 23, 1884. (No model.)

To all whom it may concern:

Be it known that I, JOHN Q. C. SEARLE, of Chicago, in the county of Cook and State of Illinois, have invented certain new and useful 5 Improvements in Car-Warmers, of which the following is a specification.

My invention relates to hot-water warming apparatus for railway-cars, and has for its object the construction of a simple device, where- 10 by the quantity of water held in the expansion-chamber may be determined at a glance, thereby regulating the quantity carried in such a manner that accidents or damage now due to an overplus or lack of water—as, for instance, 15 straining of joints by the pressure of expansion when too much water is carried, or burning the coil when empty of water—may be entirely avoided.

In hot-water warming apparatus for rail- 20 way-cars an expansion-chamber, located at the highest point of the circuit, usually upon the roof of the car, is always employed, which chamber is partially filled with water, and serves partly as an expansion-chamber, into 25 which is received the increase of volume of water by elevation of its temperature and consequent expansion, and also all air or vapor from the water, and as a reservoir from which water is drawn to make up any defi- 30 ciencies in the heating-coil or circulation-pipes by leakage or blowing off.

To insure the correct working of the expansion-chamber, it is necessary that some certain and convenient means be provided by which 35 the level or quantity of water may be read at a glance, and such an appliance is the object of my present invention, the construction and operation of which is described hereinafter.

In the accompanying drawings, Figure 1 40 shows the interior of a railway-car containing the customary heating and circulation apparatus. Figs. 2 and 3 are detached views of the devices employed to indicate the level of water in the expansion-chamber.

Similar letters of reference indicate similar 45 parts.

A is the heating-stove, of any approved form; B, a conical corrugated water-heating chamber, which displaces the coil heretofore 50 employed, the novelty and advantages of

which will be fully described in a separate application for patent; C, the flue for escape of the volatile products of combustion; D D, the pipes forming, in conjunction with the usual radiators upon one side of the car, the outflow 55 of the circuit, and E E the pipes forming, in conjunction with the radiators upon the opposite side of car, the return-flow of the circuit; F, the stand-pipe, connecting the heating-chamber B and outflow-pipes D with the ex- 60 pansion-chamber G, located upon the deck or roof of the car. f is a special fitting, the novelty and advantages of which form part of the subject-matter of an application for patent now pending, and need not be further de- 65 scribed herein. The expansion-chamber G is provided with the customary relief-valve, g, filling-cock g', and blow-out cock g".

H is a hand force-pump, arranged to supply water to the lower end of heating-cham- 70 ber B, provided with the usual receiving and discharge valves, stop-valve, and suction-pipe, all of which are fully described in a previous application for patent, and need not be fur- ther described herein.

J is a metallic case, provided with a cylind- 75 rical glass tube, j, fitting the interior or bore of case, and with screw-caps j', which in turn are threaded centrally to receive pipes J' J", respectively. The screw-caps j' are so ar- ranged that when screwed down on the case J rubber rings j", abutting against the ends of tube j are compressed and a water-tight joint made somewhat in the manner of packing glass-tube water-gages for steam-boiler use. 80 The pipe J' connects the upper end of case J with the expansion-chamber G and the pipe J", the lower end thereof with the special fit- 85 ting f, or with any other part of the system of outflow-pipes D, or, as shown by dotted lines 90 of Fig. 1, with the system of return-pipes E.

K is a hollow sheet-metal float, provided with stem k and index k', the float lying in the expansion-chamber G, the stem extending 95 down the pipe J', and the index lying in the glass tube j of case J. The float K rises and falls with the changes of level of water in the expansion-chamber G, and coincident with the change of level of float the index k' trav- 100 els up or down the tube j. Convenient gage-

points on the case J, indicating expansion-chamber entirely full, half full, or empty, enables the attendant in charge of the warming apparatus to observe at a glance the quantity 5 of water in the expansion-chamber G, and by means of pump H to restore any deficiency.

The principal objection to the use of the present hot-water warming apparatus for railway-cars is the lack of a convenient means of 10 ascertaining the state or level of water in the expansion-chamber, and, although the risks are not as great, it is as necessary that the mean level of water in the expansion-chamber G should be maintained for the safe and efficient 15 operation of hot-water warming apparatus as that the level of water in a steam-boiler should be constantly known to the attendant. The devices are simple and easily constructed, not liable to derangement, and 20 furnish a prompt and efficient means of determining the level of water carried in the expansion-chamber. The pipe J², connecting the lower end of case J with the special fitting f, or to any other convenient point of the system 25 of circulation-pipes, furnishes an open column through which water will freely pass upward or downward around index k', according to the changes of the temperature of the water in the circulation system.

30 I am aware that glass or sight gages for

steam-boilers are old and well known; but these gages are set so as to indicate in the lower portion water and in the upper portion steam, while my construction of gages enables the level of water in an elevated expansion 35 chamber or reservoir to be read off the gage J j at any desired point below the actual level thereof.

Having described my invention, what I claim is—

1. The combination, in an apparatus for warming cars, of an expansion-chamber, G, a float, K, an indicator, a glass-tube water-gage arranged below the expansion-chamber and connected therewith, and the system of circulation-pipes, substantially as described. 40

2. In a hot-water warming apparatus for railway-cars, in combination with expansion-chamber G and special fitting f, of the pipes J' J², case J, glass tube j, float K, stem k, and index k', substantially as and for the purpose 45 described.

In testimony whereof I have signed my name to the foregoing specification in the presence of two subscribing witnesses.

JOHN Q. C. SEARLE.
